UNITED STATES PATENT OFFICE.

MILTON S. KIMBLE, OF MASSILLON, OHIO.

LATHE ATTACHMENT.

SPECIFICATION forming part of Letters Patent No. 761,502, dated May 31, 1904.

Application filed July 27, 1903. Serial No. 167,093. (No model.)

To all whom it may concern:

Be it known that I, MILTON S. KIMBLE, a citizen of the United States, residing at Massillon, in the county of Stark and State of Ohio, have invented certain new and useful Improvements in Lathe Attachments; and I do hereby declare that the following is a full, clear, and exact description of the same, reference being had to the annexed drawings, making a part of this specification, and to the figures of reference marked thereon, in which—

Figure 1 is a perspective view showing my attachment properly attached to a lathe and illustrating the object desired to be operated upon properly connected. Fig. 2 is a top view of the lathe-bed, showing the object designed to be operated upon properly connected and the different parts arranged in relation with each other. Fig. 3 is a rear end view of the tool-holding base and the tool-holding arm, showing a transverse section of the pattern. Fig. 4 is a longitudinal section of the tool-holding base, showing the tracks or ways properly connected and also showing a longitudinal section of the tool-holding arm.

The present invention has relation to lathe attachments designed more especially for turning molds for bottles or other kinds of glassware; but of course I do not desire to be confined to any particular use except to carry out the object and purpose hereinafter described.

Similar numerals of reference indicate corresponding parts in all the figures of the drawings.

In the accompanying drawings, 1 represents the lathe-chuck, which is properly connected to an ordinary lathe-head and forms no particular part of the present invention, except that to carry out the objects herein-after described a lathe-head of some kind must be employed.

To the lathe-chuck 1 is attached by suitable clamps, such as 2, the mold or other article designed to be operated upon by my improved tool or attachment. In this instance the mold 3 is especially designed for forming bottles and is made in sections or halves and

the sections or halves properly connected together when attached to the chuck 1, and it will of course be understood that the mold proper should be properly centered.

To the tool post or head 4 is attached in any convenient and well-known manner the plate or bar 5, to which plate or bar is pivotally attached the tool-bar 6, to the forward end of which is attached or formed integral therewith the cutting-tool 7, which cutting-tool is formed in the usual manner and attached in any convenient and well-known way.

It will of course be understood that different tools may be attached to the tool-bar 6, reference being had to the kind of work designed to be performed.

The tool forms no particular part of the present invention within itself; but of course the tool is necessary. For the purpose of carrying out the objects hereinafter described the tool-bar 6 is provided with the elongated slot 8, through which slot is passed a bolt 9, which bolt is fixed to the plate or bar 5.

The rear end of the plate or bar 5 is provided with the tracks or ways 10 and 11, the track 10 being formed straight and at right angles to the longitudinal length of the plate or bar 5, and the track 11 is curved, the curvature being for the purpose of imparting a longitudinal movement to the tool-bar 6 by means of the pin 12, which pin is securely attached to the tool-bar in any convenient and well-known manner, and its bottom or lower end provided with the notch or recess 13, which notch or recess receives the curved track or way 11, as illustrated in Fig. 3.

It will be understood that by providing the track 10 and forming it straight as the pin 15 is moved along said track it must move in a straight line, and as the distance between the curved track 11 and the straight track 10 varies the pin 12 will be moved to and from the straight track 10, which pin carries the tool-bar with it, or, in other words, imparts longitudinal movement to the tool-bar.

To the rear end of the tool-bar 6 is slidably connected the head 14, to which head is securely attached the pattern contact-pin 15,

which pattern contact-pin is extended upward above the tool-bar 6 and below said tool-bar and its lower end provided with the notch or recess 16, which notch or recess is for the purpose of receiving the straight track or way 10, as illustrated in Fig. 3.

To the ordinary adjustable lathe tail-block 17 is attached in any convenient and well-known manner the pattern 18. One side of the pattern is provided with a curved edge 19, which curved edge necessarily corresponds with the curvature of the mold or other article designed to be operated upon and finished by the tool 7, and of course various patterns may be employed to produce various shapes of molds or other articles.

It will be understood that the tool-bar 6 must oscillate or rock upon its pivotal point, inasmuch as the cutting-tool must be kept in proper contact upon the curved surface of the article designed to be operated upon, and in order that the cutting-tool may move in a straight line to and from a given center, and thereby prevent the tool from describing an arc, the tool-bar provided with the cutting-tool is given a longitudinal movement, as it will be understood if an arc is described the cutting-tool will be moved along the surface of the article operated upon, and thereby skip some of the surface designed to be cut. In order to overcome this objection, I provide the curved track or way 11, which curved track or way moves the tool-bar 6 longitudinally by means of the pin 12 and its recess 13, thereby causing the tool end of the bar 6 to move to and from a common center in a line at right angles drawn transversely through the mold or article designed to be operated upon, and as the tool is moved longitudinally during the time it is oscillated it rocks upon its pivot pin or post, which pivot pin or post is held in fixed position with reference to the tool-bar.

It will be understood that the rear end of tool-bar must also move longitudinally by the oscillation of said tool-bar; but in order to prevent the pattern-pin 15 from any longitudinal movement with reference to the tool-bar 6, or, in other words, to follow the longitudinal movement of the tool-bar, the straight track or way 10 is provided, by which means the pattern-pin 15 moves in a straight line to and from the pattern 18 and describes no arc as the tool-bar oscillates.

In order to compensate for the straight movement of the pin and at the same time carry the tool-bar at its rear end, the sliding block 14 is provided, which sliding block moves back and forth or to and from a given center as the tool-bar oscillates.

The sliding block 14 is held in place by means of the tongues and grooves 21. For the purpose of assisting in preventing any springing or bending of the tool-bar 6 the

cap-bars 22 are provided, which bars may be formed integral with the plate or bar 5.

It will be understood that the pattern 18 should be held in a rigid position, and in order to assist in doing so the brace 23 is provided, which brace is connected to the front or forward end of the pattern 18 in any convenient manner and is attached to the rear portion of the lathe at any desired point, as the only object is to steady the pattern.

It will be understood that the pattern-pin 15 should be extended upward a sufficient distance to come in proper contact with the working edge of the pattern 18.

For the purpose of holding the tool-bar in true alinement when out of contact with the pattern the springs 24 are provided, which springs may be of the form shown, or they may be of any other desired form.

Having fully described my invention, what I claim as new, and desire to secure by Letters Patent, is—

1. In a lathe attachment the combination of a tool-carriage carrying a plate provided with transverse tracks or ways, one of said tracks being straight and the other curved in such manner as to impart longitudinal motion to the tool, a slidingly-pivoted tool-bar having fixed thereto a pin, said pin having a recessed end to engage the curved track, a sliding head connected to the tool-bar and provided with a pin having a recess at its bottom or lower end adapted to engage the straight track, said pin connected to the sliding head adapted to engage a working pattern, said working pattern having curved edges corresponding with the curvature of the finished article, substantially as and for the purpose specified.

2. In a lathe attachment the combination of a lathe-carriage, said carriage having connected thereto a plate or bar, a tool-bar pivotally connected to the plate or bar and provided with an elongated slot at its pivotal point, transverse tracks or ways fixed to the plate or bar, one of said tracks being curved in such a manner as to impart longitudinal motion to the tool and the other straight, a sliding head connected to the tool-bar, pins adapted to engage the track or way, one of said pins adapted to engage the straight track and the other adapted to engage the curved track, said pins fixed to the tool-bar and the sliding head respectively, and a fixed pattern, the pin of the straight track adapted to engage the fixed pattern, substantially as and for the purpose specified.

In testimony that I claim the above I have hereunto subscribed my name in the presence of two witnesses.

MILTON S. KIMBLE.
